HARRY BILLMEYER, OF WASHINGTONVILLE, PENNSYLVANIA.

SAFETY SNAP HOOK.

Application filed April 5, 1922. Serial No. 549,673.

To all whom it may concern:

Be it known that I, HARRY BILLMEYER, a citizen of the United States, residing at Washingtonville, in the county of Montour 5 and State of Pennsylvania, have invented a new and useful Safety Snap Hook, of which the following is a specification.

This invention relates to snap hooks.

The object is to provide a hook of this 10 class for use in connection with different parts of harness, which may be easily and quickly operated to engage a ring or other device by a single operation and to effectually prevent the accidental disengagement 15 of the ring when the parts are connected.

Another object is to provide a simple 20 and cheaply manufactured hook of this class, wherein the said ring or other part may be readily removed from the hook by simply pressing upon a lever to compress 25 a retaining spring and to remove a guard arm out of the path of movement of the ring, when a free and open passageway for the latter is provided without any projecting parts to interfere with the quick disengagement of the ring from the hook.

A full and complete understanding of 30 the invention may be obtained from a consideration of the following detailed description, taken in connection with the accompanying drawing forming a part of this specification; it being understood that while the drawing shows a practical form of the invention, the latter is not confined to strict 35 conformity therewith, but may be changed or modified, so long as such changes or modifications mark no material departure from the salient features of the invention, as specifically pointed out in the appended 40 claims.

In the drawing, in which similar reference characters designate corresponding parts throughout the several figures:

Figure 1 is a side elevation of the improved hook having a ring connected therewith;

Figure 2 is a longitudinal, sectional view 50 of the same, the locking lever being depressed to remove the guard arm out of the path of movement of the ring, the latter being shown in the act of removal;

Figure 3 is a side elevation of the hook showing the position of the parts when the ring is about to leave the hook, said ring 55 being in section;

Figure 4 is a top plan view of the connected hook and ring;

Figure 5 is a side elevation of a slightly modified form of the invention.

In the drawing there is illustrated a snap hook having a body member 1, provided at one end with a spring socket 2, and an integrally formed loop 3 for engagement with any part of harness, the parts, as thus far described, being of ordinary construction.

Mounted in the socket, in the usual manner, is a stiff steel leaf spring 4, having its adjacent end 5, returned to lie flat upon the bottom of the socket and to be retained 70 therein by opposed, inwardly-directed lugs 6, the other end of the spring being elongated to extend towards the other end of the hook, the free end of the spring normally lying in spaced relation to the body of the hook. The socket portion of the base is wider than the forwardly extended shank 7 which, at the front end is returned to form a ring-receiving loop 8, having an internal diameter to receive rings of different sizes. 80 Integrally connected with the loop 8 is an upwardly and rearwardly extending arm 9, the rear end of which lies substantially in line with the center of the base of the hook and in spaced relation to the same, forming 85 a projection at 9°. At the rear end of this extension, a socket 10 is formed, open at the rear end and bottom of the same toward the shank 7, and adapted to receive a bell-crank lever provided with a hub 11, having 90 an actuating arm 12, and a guard arm 13, arranged substantially at right angles to each other and formed integrally with said hub. The hub is mounted between the walls of the extension comprising the socket 10, 95 and the several members are suitably apertured for the reception of a horizontally disposed pivot pin 14. The actuating arm 12 normally lies in a horizontal position or parallel with the body member, the free end 100 of the spring 4 bearing against the underside of the arm 12, and having its terminal in close proximity with the hub of the bell-crank lever, the guard arm extending perpendicularly across the space between the 105 base or shank of the hook and the end of the extension 9. The free end of the actuating arm 12 is provided with an enlarged head 15 to facilitate grasping by thumb or finger of the operator, and the same is 110

rounded so as to prevent the different parts of the harness from catching thereon, and the guard arm 13 is slightly tapered and curved forwardly at its lower end where it 5 terminates in a relatively narrow edge adapted to swing down into a depression or seat 7^a formed in the upper face of the shank of the hook for the purpose.

When the bell-crank lever is rocked by 10 pressing downwardly on the actuating arm 12, the lower end of the guard arm 13 is swung forwardly and upwardly and abuts against the projecting portion 9^a at the junction of the ring loop 8 and the adjacent, 15 lower portion of the extension 9, as shown in Figure 2, thus preventing the ring R from accidentally entering the space above the arm 13, so that the said ring is free to be passed rearwardly, above the free end of the 20 spring, pushing the actuating arm upwardly and thus caused to be disengaged from the hook. The forward, free end of the spring, by being extended sufficiently forward to engage the bell-crank lever near to its 25 pivotal point, is thus made sufficiently long to strike against the upper face of the shank when depressed by the free, headed end of the arm 12, and thus effectually prevent the ring from passing beneath the said 30 spring.

In Figure 5 a slightly modified form of the hook is shown, wherein the ring loop 8^a comprises the entire end of the hook, the shank being bent in a semi-circle to return 35 upon itself and terminating in the socket member as in the first described form of the invention.

In snap hooks, as heretofore constructed, the depression of the retaining spring, which 40 is usually quite stiff and powerful, has depended upon the pressure of the thumb or finger of the operator, and this interferes with the free passage of the ring or other attached part, besides being difficult for some 45 persons to accomplish. Those hooks having bell-crank or other levers for increasing the power to compress the retaining spring, generally require a second operation by the hand of the operator to free the end of the 50 spring from contact with the said lever, in order to provide a passageway for the ring, and since one hand is engaged in holding the hook while the other is engaged in passing the ring rearwardly from the loop of 55 the hook, more or less trouble is encountered.

In order to avoid these difficulties, the present snap hook has been devised, whereby the harness ring, or other part, may be quickly and easily engaged therewith by 60 simply passing the ring over the end of the hook to bear upon the spring and by a forward pull on the same, cause it to compress the spring and to pass between the free end thereof and the actuating member of the 65 bell-crank lever, thence abutting the guard

arm and rocking the same forwardly to pass beneath the end of the same and to find free access to its seat in the front end of the loop of the hook.

In like manner the ring may be as easily 70 detached from the hook, as it will be seen that by the depression of the spring, through the pressure of the hand of the operator upon the actuating member of the bell-crank, the latter is depressed and forces the end of the 75 spring into contact with the base of the hook so that the ring finds no interference thereby, and in the meantime, the guard arm of the lever has been raised out of the way of the ring, as clearly shown in Figure 2 of the 80 drawing, and the said ring may be freely passed backwardly to strike the actuating arm, rocking the latter and thence slipping out between the same and the free end of the 85 spring.

From the foregoing it will be seen that a simple snap hook structure has been provided, which may be readily manufactured at a low cost, having few parts to become deranged, and having effective means for preventing the accidental disengagement of a ring or other part of harness to which the hook may be connected, and that the said ring may be easily placed within the hook by a single pressing action of the same, or disengaged therefrom by simply pressing the lever by the finger and moving the ring in the proper direction.

What is claimed is:

1. A snap hook comprising a body having a ring loop with a socket in the end thereof, a leaf spring carried by the body and having its free end terminating adjacent to said socket and adapted to be depressed to contact with the inner face 100 of the body, and a bell-crank lever having arms substantially at right angles to each other and pivotally mounted in the socket, the outer arm being adapted to normally extend outwardly from the socket and substantially parallel to the body and to rest upon the free end of the spring to depress the same, the inner arm of the lever extending across the space between the socket and the body, said lever being rockable to a position where the outer arm, bearing against the spring, forces the free end thereof against the inner face of the body and the inner arm extends substantially parallel to the free end portion of the spring and contacts with the ring loop to guide the ring into the space between said inner arm and the free end portion of the spring.

2. A snap hook comprising a body and a hook, having a contracted ring-receiving loop, an upwardly curved arm providing a projection at its junction with the ring-receiving loop, and a socket at the free end of the hook which opens toward the body, a leaf spring fitted within the body and hav-

ing its free end extended upwardly from the body and terminating adjacent said socket, a bell-crank lever having arms substantially at right angles to each other and pivotally mounted in the socket beyond the end of the spring, one arm being adapted to normally extend outwardly from the socket and overhang the free end of the spring and contact with said spring when depressed, the other 10 arm of said lever extending across the space between the socket and the body, the latter having a seat to receive the end of said arm, said arm being adapted to contact with said projection when the lever is rocked so as to guide the ring outwardly between said arms 15 and above the free end of the spring.

In testimony, that I claim the foregoing as my own, I have hereto affixed my signature.

HARRY BILLMEYER.
